Bret G. Fischer.

By

F. G. Fischer

Attorney

UNITED STATES PATENT OFFICE.

LAWRENCE W. ANDREWS, OF KANSAS CITY, MISSOURI.

OIL PUMP.

Application filed July 17, 1922. Serial No. 575,695.

To all whom it may concern:

Be it known that I, LAWRENCE W. ANDREWS, a citizen of the United States, residing at Kansas City, in the county of 5 Jackson and State of Missouri, have invented certain new and useful improvements in Oil Pumps, of which the following is a specification.

My invention pertains to force feed pumps 10 and while it may be used wherever a pump of this character is desired it is intended more particularly for internal combustion engines which heretofore have depended on the splash and gravity system for circulation 15 of the lubricating oil.

The objects of the invention are to provide a pump of simple and inexpensive construction, which is reliable in operation and can be readily installed on the engine.

20 Referring now to the accompanying drawing which illustrates the invention:—

Fig. 1 is a side elevation of an engine provided with the pump.

Fig. 2 is an enlarged fragmentary section 25 of a portion of the engine with the oil pump in elevation.

Fig. 3 is a vertical sectional view of the oil pump on line III of Fig. 2.

Fig. 4 is a horizontal section on line 30 IV—IV of Fig. 3.

Fig. 5 is a plan view of a rocker arm employed in carrying out the invention.

As shown by the drawings, the engine A is 35 equipped with the sump B, the breather pipe C, the valve stems E, the push rods F, the plates D whereby access may be had to the valve stems E and the push rods F for inspection and adjustments.

40 All of the foregoing are of usual construction, the invention residing in the pump which will now be described in detail.

2 designates the pump which embodies a vertically-disposed cylinder 4 provided at its lower portion with a lateral extension 6. 45 The bore 8 of the pump communicates with an oil duct 10 leading downwardly through a boss 12 at the lower end of the cylinder 4. The duct 10 communicates with an oil duct 14 extending laterally through a portion of 50 the extension 6 and thence upwardly through said extension, as disclosed by Fig. 3. The duct 10 is equipped with an induction valve 16 while the duct 14 has an eduction valve 18 therein.

55 20 designates the pump plunger which consists, preferably, of a solid piece of metal

reciprocably mounted within the bore 8, oil being prevented from seeping upwardly between the wall of the bore 8 and the plunger 20 by a stuffing box 22.

60 The upper end of the plunger 20 projects from the stuffing box 22 and has a recess 24 in which a pin 26 and a spring 28 are mounted, the latter of which forces the former upwardly to hold it constantly in engagement with the rounded terminal 30 of a rocker arm 32 mounted on a pivot 34 at the upper end of a bracket 36 formed integral with the upper portion of the cylinder 2. The opposite end 33 of the rocker 70 arm 32 is bifurcated to straddle the lower end of one of the valve stems E and rests upon a cap 38 loosely mounted upon the upper end of the push-rod F to provide a relatively broad bearing surface for the bifurcated end 33 of the rocker arm 32. The bracket 36 is fixed to a plate 40 which is substituted for one of the plates D and has a slot 42 through which the rocker arm 32 extends to the cap 38.

75 43 designates a coil spring interposed between the bottom of the cylinder bore 8 and the lower end of the plunger 20 to force the same upwardly after each downward stroke imparted thereto by the push rod F and the 80 rocker arm 32.

85 The upward stroke of the plunger 20 may be restricted by a member 46 extending loosely through the lateral extension 6 and a guide 48, which latter is formed integral 90 with the upper portion of the cylinder 2. The upper end of the member 46 is bent at right angles to project into the path of the plunger 20, while the lower end of said member 46 is threaded and provided with a 95 nut 50 which coacts with a spring 52 in adjusting said member 46 upwardly or downwardly to permit a greater or less stroke of the plunger 20. The spring 52 is interposed between the top of the lateral extension 6 100 and a collar 54 secured to the member 46, the upper portion of which latter is rectangular in cross section to fit the corresponding opening in the guide 48 and thus prevent said member 46 from rotating and carrying its lateral extension out of the path 105 of the plunger 20.

110 The pump 2 is ready for installation on the engine A by removing one of the plates D and substituting the plate 40 after which the boss 12 of the cylinder 4 is connected to the sump B by an inlet pipe 44, while the

lateral extension 6 is connected to the breather pipe C by an outlet pipe 66 which communicates with the outlet end of the duct 14.

5 The operation of the pump 2 is substantially as follows: At each upward stroke of the push rod F the plunger 20 is forced downwardly through the intermediacy of the rocker arm 32, and at each downward stroke of the push rod F said plunger 20 is forced on its upward stroke by the spring 48. As the plunger 20 moves upwardly it sucks the oil from the sump B, the valve 16 being pushed upwardly by the infusing 10 oil until the plunger 20 reaches the end of its upward movement, whereupon the valve 16 closes and entraps the oil. Then as the plunger 20 moves downwardly the entrapped oil is forced to the breather pipe C 15 through the duct 14 and the outlet pipe 66, raising the valve 18 on its outward passage. As the plunger 20 reaches its downward stroke the valve 18 closes and prevents any oil in the outlet pipe 66 from running back 20 into the duct 14 and thus excluding a fresh supply of oil.

Should it be found that too much oil is being pumped the stroke of the plunger 20 is reduced by lowering the member 46, while 30 if insufficient oil is being pumped the plunger 20 is permitted to move through a longer stroke by adjusting the member 46 upwardly the desired distance.

The pin 26 is constantly held in contact 35 with the adjacent end of the rocker arm 32 by the spring 28 irrespective of the length of the stroke of the plunger 20, thus obviating lost motion and the noise incident thereto which would otherwise occur if the rocker 40 arm 32 struck the upper end of the plunger 20 when forcing the same on its downward stroke. The last-mentioned feature also obviates wear on the engaging parts, while wear of the bifurcated end 33 of the rocker 45 arm 32 is reduced to a minimum by the broad surface presented thereto by the cap 38.

From the foregoing description, taken in connection with the drawing, it is apparent 50 that I have produced an oil pump embodying the advantages above pointed out, and while I have shown and described the preferred construction, combination and arrangement of parts, I reserve the right to 55 make such changes as properly fall within the spirit and scope of the claims.

Having thus described my invention, what I claim and desire to secure by Letters Patent, is:

60 1. An oil pump for internal combustion engines consisting of a cylinder having in-

duction and ejection pipes connected to said engine, a plunger reciprocably mounted in said cylinder and projecting from the upper end thereof, means for adjusting the length 65 of the plunger stroke, a rocker arm actuated by the engine for moving said plunger in one direction, cushioning means interposed between the upper portion of the plunger and said rocker arm, and means for moving 70 the plunger in an opposite direction to that effected by the rocker arm.

2. An oil pump for internal combustion engines consisting of a cylinder having induction and ejection pipes connected to said engine, a plunger reciprocably mounted in said cylinder and projecting from the upper end thereof, means for adjusting the length 75 of the plunger stroke, a rocker arm actuated by the engine for moving said plunger in one direction, a pin mounted in the upper end of the plunger, a spring carried by the plunger to yieldably hold said pin against the rocker arm, and means for moving the plunger in an opposite direction to that effected by the rocker arm.

3. An oil pump for internal combustion engines consisting of a cylinder having induction and ejection pipes connected to said engine, a plunger reciprocably mounted in said cylinder, means for actuating said plunger, a member independent of said actuating means extending into the path of the plunger to limit the stroke of the same, threaded means for adjusting said member 95 to adjust the stroke of the plunger, and resilient means coacting with said threaded means in adjusting the member.

4. An oil pump for internal combustion engines consisting of a cylinder having induction and ejection pipes connected to said engine, a plunger for forcing oil through the cylinder, valves to prevent backward flow of oil in the cylinder, a rocker arm actuated by the valve mechanism of the engine 100 for imparting motion to the plunger, a bracket formed integral with the cylinder, a plate secured to said bracket and adapted to be secured to the engine, a member independent of said rocker arm extending through guides on the cylinder and projecting into the path of said plunger to limit the stroke of the same, and means for adjusting said member to adjust the stroke of the plunger.

In testimony whereof I affix my signature, in the presence of two witnesses.

LAWRENCE W. ANDREWS.
